UNITED STATES PATENT OFFICE.

JOHAN AUGUST JANSSON, OF HAGALUND, SWEDEN.

DEVICE FOR SUPPORTING BODIES OF VEHICLES.

SPECIFICATION forming part of Letters Patent No. 623,787, dated April 25, 1899.

Application filed December 29, 1897. Serial No. 664,371. (No model.)

To all whom it may concern:

Be it known that I, JOHAN AUGUST JANSSON, a subject of the King of Sweden and Norway, and a resident of Hagalund, Stockholm, in the 5 Kingdom of Sweden, have invented certain new and useful Improvements in Equalizing Devices for Supporting the Bodies of Vehicles, of which the following is a specification.

This invention relates to the class of devices 10 for supporting the bodies of vehicles—such as railway-cars, wagons, carriages, and sledges—wherein equalizing levers and springs are employed between the axles and the vehicle-body to cause the latter to move up and down 15 parallel with itself as the load varies and to maintain the body substantially parallel with the road-bed when the load is unequally distributed.

In the construction herein shown the pairs 20 of equalizing-levers are fulcrumed under the vehicle-body, the levers of the pair being situated near the respective sides of the vehicle and their inner arms being bent inward so as to meet near or at the longitudinal axis of the 25 vehicle, where they take either directly or through an intermediate lever under a transverse spring secured to the body substantially at the middle of its length. In the form employed for ordinary street-cars and wagons 30 the pairs of levers are fulcrumed on the respective axles and their inner longer arms take directly under the spring; but in long railway-cars having bogie-trucks the pairs of levers are fulcrumed on the car-body and 35 there are intermediate levers to take under the spring or pair of springs.

In the accompanying drawings several embodiments of the invention are illustrated.

Figures 1, 2, and 3 are respectively a cross- 40 section, a side elevation, and a plan of a relatively short railway-car provided with this invention. Figs. 4, 5, and 6 are respectively a side elevation, an end elevation, and a plan of a longer railway-car provided with this invention. Figs. 7, 8, and 9 are respectively 45 an end elevation, a side elevation, and a plan of a wagon having this invention applied thereto.

Referring primarily to Figs. 1, 2, and 3, it 50 will be seen that underneath the car-body there are four levers arranged in pairs, the levers of the pairs being under opposite sides

of the body. The shorter outer arms of these levers are designated by A and the longer inner arms by B. The levers are fulcrumed on 55 the car-axle, their shorter arms extending out under the ends of the car and coupled to a cross-bar or shaft D, mounted in brackets under the car-body C. The longer arms B of the pair of levers are bent inward to the longitudinal axis of the car and where they are secured together. The pairs of levers are coupled together at the middle of the length of the car-body by a pin E. A strong spring F is placed transversely under the car-body 60 between said body and the coupled ends of the pairs of levers. This spring is coupled to the car-body at its ends, preferably by links, and it is supported at its middle on the links at the coupling-point E. As the axles of the 65 cars are always at a fixed elevation and form the fulcrums of the pairs of levers and the inner ends of the levers are coupled together, it will be evident that any depression of the body at one point will be equally distributed 70 over the whole body. The ratio between the arms of the levers can be conveniently taken as one to two, thus making the weight on the spring equal to one-third of that of the load. 75

Figs. 4, 5, and 6 represent the application 80 of the invention to what is called a "bogie-car." In this construction the pairs of levers H have their outer arms coupled to the bogie-truck, are fulcrumed on the car-body, and have their inner arms brought by bending 85 into the longitudinal axis of the car and coupled to the outer end of an intermediate lever I. This lever is fulcrumed on the car-body, and the inner ends of the two levers I take under springs K, interposed between 90 them and the body of the car.

Figs. 7, 8, and 9 show an ordinary four-wheeled wagon to which this invention is applied. The system of levers shown in these views is substantially the same as that seen 95 in Figs. 1, 2, and 3. The pairs of levers are not, however, fulcrumed directly on the axles, but on a frame L, mounted on the axles. This frame is pivotally attached to the rear axle, as seen at L² in Fig. 7. 100

The leading feature of this invention consists in bringing the two levers of the pair inward substantially to the longitudinal axis of the vehicle and supporting the transverse

spring at the middle of the body directly or indirectly on the levers at the axis of the car.

Three applications of the invention have been illustrated herein; but it will be obvious 5 that the construction may be varied to suit other applications without departing materially from the invention.

Having thus described my invention, I claim—

10 1. The combination with the wheels, axle and body of a vehicle, and a transverse spring situated under said body, of levers extending lengthwise of the vehicle and fulcrumed under the body at its respective sides, the

15 arms of said levers at one side of the fulcrum being bent inward to the longitudinal axis of the body and coupled to said transverse spring, whereby the latter is interposed between said levers and the body, substantially 22 as set forth.

25 2. The combination with the wheels, axles and body of a vehicle, and a transverse spring situated under the middle of said body, of two pairs of levers under the ends of the vehicle-body, the levers of each pair being fulcrumed under the body at its respective sides and the inner arms of the levers of the pair 30 bent inward and connected together substantially in the longitudinal axis of the vehicle under said spring, whereby when the vehicle is loaded, the spring will be compressed between the said levers and the body, substantially 45 as set forth.

30 3. The combination with the wheels, axles and body of a vehicle, and a transverse spring

35 situated under the middle of said body, of two pairs of levers under the ends of the vehicle-body, the levers of each pair being fulcrumed under the body at its respective sides and the inner arms of the levers of the pair 40 bent inward and connected together substantially in the longitudinal axis of the vehicle under said spring, whereby when the vehicle is loaded, the spring will be compressed between the said levers and the body, substantially 45 as set forth.

4. The combination with the wheels, axles and body of a vehicle, and a transverse spring F, under the body at the middle of its length and connected thereto at its ends, of two pairs 50 of levers, fulcrumed on the respective axles of the vehicle, the shorter arms, A, of the levers extending out under the respective ends of the said body and coupled thereto and the longer arms, B, of the levers of the pair bent 55 inward and connected together, the inner arms of the levers taking under the middle of the transverse spring, substantially as set forth.

In witness whereof I have hereunto signed 60 my name in the presence of two subscribing witnesses.

JOHAN AUGUST JANSSON.
